UNITED STATES PATENT OFFICE.

CHRISTIAN FRIEDRICH GLOYSTEIN, OF HENDERSON, KENTUCKY.

MANUFACTURE OF CONCENTRATED TOBACCO EXTRACT.

No. 899,865.

Specification of Letters Patent.

Patented Sept. 29, 1908.

Application filed January 10, 1908. Serial No. 410,210.

To all whom it may concern:

Be it known that I, CHRISTIAN FRIEDRICH GLOYSTEIN, a subject of the German Empire, residing at Henderson, in the county of Henderson and State of Kentucky, have invented a new and useful Improvement in the Manufacture of Concentrated Tobacco Extracts, of which the following is a specification.

10 The invention consists of an improved method of treating raw aqueous tobacco-extract, whereby I obtain an extract free from sediment.

Raw aqueous tobacco extract usually contains in addition to suspended dirt, incident to the process of obtaining the extract, a certain quantity of albumen, which when the extract is concentrated forms an undesirable precipitate. I have discovered that 20 this precipitation may be readily avoided by converting the albumen into peptones, etc.

The method consists in heating the raw aqueous tobacco extract to a temperature above 100° C. and under pressure until the albumens have been transformed into peptones. I have found that if the temperature be raised to about 160° C. and the pressure be kept at about 100 pounds to the square inch, the transformation of the albumens, 25 whether they are contained in the extract in dissolved or undissolved condition, is complete in about an hour. The same result may be obtained although the temperature and pressure be varied provided the temperature 30 be kept above 100° C.

In the accompanying drawing is shown in side elevation partly broken away, a simple apparatus for carrying out the process.

A strong tank A, preferably made of steel 40 is provided with heating coils, b, of copper or brass, a gage c, a man-hole d, and convenient inlets and outlets for the extract, e and f respectively.

The tank, A, is filled to one-half or three-fourths of its capacity with raw aqueous 45 tobacco extract. Then steam of sufficient pressure is applied to the heating coil, b, until the tobacco extract has reached the temperature of about 160° C. and there is a pressure of about 100 pounds to the square 50 inch on the tank, which will be shown by the gage, c. The heat and pressure is now kept constant for about an hour. After the steam is cut off and the tobacco extract sufficiently cooled down, the extract can be drawn 55 off and filtered, to be cleaned of its suspended dirt, and then concentrated. In the same manner the precipitated albumen of a tobacco extract, if mixed with a sufficient quantity of water, for example one pound 60 water to one pound sediment of albumen and treated as above described, can be dissolved again and will stay dissolved forever.

I claim as my invention:

1. The process of treating tobacco extract 65 which consists in subjecting the same to a temperature above 100° C. under pressure to transform the albumens present into peptones.

2. The process of treating tobacco extract 70 which consists in heating the same to a temperature of approximately 160° C. under a pressure of approximately 100 pounds to the square inch for about one hour, to transform the albumens present into peptones. 75

3. As a new product, a tobacco extract having its normal albumens peptonized to prevent sediment.

In testimony whereof I have signed my name to this specification, in the presence of 80 two subscribing witnesses.

CHRISTIAN FRIEDRICH GLOYSTEIN.
